(57) **CLAIM**

The ornamental design for a notebook computer, as shown and described.

DESCRIPTION

FIG. 1 is a top perspective view of a notebook computer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof;

FIG. 9 is an enlarged view of the portion 9 delineated in FIG. 1;

FIG. 10 is an enlarged view of the portion 10 delineated in FIG. 2;

FIG. 11 is an enlarged view of the portion 11 delineated in FIG. 3;

FIG. 12 is an enlarged view of the portion 12 delineated in FIG. 6;

FIG. 13 is an enlarged view of the portion 13 delineated in FIG. 7; and,

FIG. 14 is an enlarged view of the portion 14 delineated in FIG. 8.

The evenly-dashed broken lines in the drawings illustrate portions of the notebook computer that form no part of the claimed design. The dot-dashed broken lines encircling portions of the claimed design that are shown in enlargements form no part of the claimed design.

1 Claim, 6 Drawing Sheets
